FIG. 4.
Maurice X. C. Weinberger

INVENTOR

UNITED STATES PATENT OFFICE

1,999,222

CIGARETTE

Maurice X. C. Weinberger, Brooklyn, N. Y., assignor to Self Extinguishing Cigarette Corporation, a corporation of New York

Application April 7, 1933, Serial No. 664,888

3 Claims. (Cl. 131—52)

My invention relates to an improvement in cigarettes, and has particular reference to the preparation of the envelope or container, herein called the paper, of the cigarette. A lighted cigarette burns continuously till wholly consumed when left to itself. It is rapidly self-consuming and burns with a high degree of heat. The dangers from, and damages caused by, neglected or laid-aside lighted cigarettes are universally known and there is general demand for the elimination of this evil. Furthermore, an uninterrupted self-consuming cigarette is an economic waste.

A cigarette burns the way it does—continuously and self-consuming—for two major reasons, both inherent in the present processes of manufacture: First, because the paper material is a highly inflammable substance of a very even texture, uniform from end to end, and requires but a small amount of oxygen to sustain continuous combustion. Second, because the manner of packing the tobacco particles within the paper is such at the present time, as to leave a continuous air space between tobacco and paper, which air space provides additional paper-surface-exposure to oxygen supply.

One object of my invention is to provide a cigarette that burns freely, but ceases burning, and thus extinguishes itself, at a predetermined zone or at predetermined zones and within limited periods of time, if left alone, as when not being smoked.

Another object of my invention is to provide a cigarette which burns freely and with less heat by reason of a self-limiting of the oxygen supply which in turn provides a cool smoke and a minimum of smoke fumes.

To the above and other ends the invention contemplates a cigarette structure in which the lengthwise combustion-continuity of the paper is impaired, as will hereinafter become apparent from the following description taken in connection with the accompanying drawing, in which—

Fig. 1 is a longitudinal sectional view of one form of a cigarette embodying the invention; Fig. 2 is a view similar to Fig. 1 and showing a slightly modified form of the invention; Fig. 3 is a perspective view of a cigarette paper from which the envelope of the cigarette of Fig. 1 is formed; Fig. 3A is a perspective view of a modified form of cigarette paper from which the cigarette of Fig. 2 is formed; Fig. 3B is a fragmental, perspective view of another modified form of cigarette paper; Fig. 3C is a face view of another modified form of cigarette paper, and Fig. 4 is a view similar to

Figs. 1 and 2 and showing another modified form of cigarette, which embodies the present invention and in which the paper of Fig. 3C is employed as a wrapper.

In producing the cigarette shown in Fig. 1, I employ a cigarette paper 1 to which a plurality of strips of similar paper 2 are suitably secured as by agglutination. These strips are about $\frac{1}{16}$ " wide and are arranged in a parallel relation to each other across the width of the cigarette paper so that they will be disposed transversely of the finished cigarette, the strips being spaced about $\frac{1}{4}$ " from each other. Inasmuch as the cigarette paper is so folded or rolled about the filler or tobacco contents in the manufacture that the strips assume the form of parallel concentric bands 4 disposed within the cigarette envelope or container, they are substantially invisible from the outside of the finished article.

Preparatory to folding or rolling the cigarette paper about the tobacco, the inner surface of the strips of the paper 2 is coated with a suitable agglutinating substance of the character employed, for example, in sealing the overlying margins of the paper to each other following the cigarette rolling operation. Upon placing tobacco on the paper preparatory to the cigarette rolling operation, particles of the tobacco owing to the presence of the agglutinating substance are attached to the inner surface of the paper strips 2. These attached particles are more or less intermingled with the bulk of the tobacco content of the finished cigarette and function to exclude the oxygen supply from the inner surface of the cigarette envelope in the vicinity of the paper strips so that the cigarette becomes self-extinguishing if left alone as when not being smoked.

In producing the cigarette shown in Fig. 2, the same general procedure as stated in connection with the production of the cigarette of Fig. 1 is employed, with the result that these two forms of cigarettes are identical except for the fact that in the cigarette of Fig. 2 the parallel concentric bands 4' are differently positioned with respect to the previously described concentric bands 4 of Fig. 1. This different disposition of the bands 4' is due, of course, to the fact that the paper strips 2' are attached to the cigarette paper 1' as shown in Fig. 3A.

If desired, the strips of paper 2 and 2' above described may be supplanted by a superimposed sheet of paper 2'', as shown in Fig. 3B, which is suitably secured to the cigarette paper 1'' as by agglutination, it being noted that the superimposed sheet of paper is provided transversely of

itself with a plurality of groups of openings 5 which are so spaced longitudinally of the cigarette paper as to provide, in effect, a plurality of imperforate transversely disposed tobacco-carrying areas to which particles of tobacco attach themselves in the presence of an agglutinating substance with which the superimposed sheet of paper is provided. The imperforate transverse portions of the superimposed sheet of paper 2" 10 assume the form of a plurality of parallel concentric bands, corresponding to the concentric bands 4 and 4' upon completion of the cigarette rolling operation, so that they, together with the particles of tobacco adhering thereto, serve, like 15 the concentric bands 4 and 4' with their adhering particles of tobacco, to render the cigarette self-extinguishing. Instead of employing the strips of paper 2 or the strips of paper 2' or the sheet of paper 2" as and for the purpose hereinbefore 20 described, a cigarette, of the form shown in Fig. 4 and which embodies the present invention, may be produced with the cigarette paper 2''' shown in Fig. 3C. As to the cigarette paper 2''', it is to be noted that the agglutinating substance, as 25 shown at 6, is applied directly to and extends transversely of the tobacco-receiving surface of the paper relatively near one end thereof. Upon placing tobacco on the paper 2''' preparatory to the cigarette-rolling operation, particles of the tobacco become attached, through the medium of 30 the agglutinating substance, directly to that paper and present, in association with the agglu-

tinating substance, a band 4" in the finished cigarette as shown in Fig. 4, which band renders the cigarette self-extinguishing at and in the vicinity of the band-like zone which is occupied by the adhering tobacco particles.

The term "band" as used in this specification implies a stripe of agglutinating substance on the inner surface of the wrapper of a cigarette.

Aside from the different forms of the invention herein shown and described, other modifications 10 may be employed without departing from the spirit of the invention or the scope of the following claims.

What is claimed is:

1. A cigarette having on the inside of its wrap- 15 per a band of agglutinating substance which attaches certain of the tobacco fibres to the wrapper.

2. A cigarette comprising a filler and an envelope embracing said filler, and having attached 20 to its inner wall particles of the filler material, said particles being disposed in a band-like zone intermediate the ends of said envelope.

3. A cigarette comprising a filler and an envelope embracing said filler and having attached 25 to its inner wall particles of the filler material, said particles being disposed in a band-like zone intermediate the ends of said envelope and intermingled with the remaining portion of the filler content.

MAURICE X. C. WEINBERGER.
